WINDMILL

Vaughan L. Andrew, Superior, Wis.

Application March 25, 1935, Serial No. 12,815

9 Claims. (Cl. 184—4)

This invention relates to windmills, and has special reference to a novel oiling system therefor, and is an improvement over the type of oiling system illustrated in my former Patent No.

5 1,579,343, granted to me April 6th, 1926.

The principal object of my present invention is to provide a windmill head wherein perfect balance and strength is accomplished by a new arrangement of gearing, allowing the wind wheel 10 shaft to be placed in line with the mechanism housing thereby balancing the over-hang and placing the loads directly over the center of the tower. Beveled gears are used, and, operating in oil, they cause considerable pressure to be 15 created therein, and this pressure is utilized in directing the flow of a portion of the oil so that it will lubricate the long bearing of the pinion shaft, and this forms another paramount object of my present invention.

20 It is a further object of the invention to provide a windmill head which may be completely disassembled with a minimum of effort, so that the parts are readily accessible for repair or for other purposes.

25 Still other objects and advantages of the invention will appear in the following description thereof.

Referring now to the accompanying drawing, forming part of this application, and wherein 30 like reference characters indicate like parts:

Figure 1 is a side elevation, partly in section, of the oil reservoir and pinion shaft bearing assembly, of my improved windmill head.

Figure 2 is a top plan view of the same.

35 Figure 3 is a face elevation of my improved pinion.

Figure 4 is a section on the line 4—4 of Figure 2.

The oil reservoir or gear housing is indicated 40 at 1, toward one side of which the rocker arm 2 is pivotally supported as at 3, and the opposite or free end is attached to the pump plunger rod 4 as by the ball and socket joint indicated at 5. A bevelled ring gear is indicated at 6, it being 45 fixed to the shaft 7 each end of which extends through a side wall of the housing and is supported within a cup bearing member 8 removably attached to the side walls by means of tap bolts 10.

50 A pitman indicated at 11 connects the rocker arm 2 with an eccentric hub 9 integrally formed on the back of the gear 6, and as the gear rotates it causes the rocker arm to reciprocate, and the arm in its cycle of travel is raised and lowered above and below a plane with the upper-

most circumferential edge of the gear, and when there is oil in the reservoir it is obvious that the same will be carried to a certain extent around on the gear 6.

5 A laterally extending web 12 is formed on the side of the rocker arm, which web, between the pitman 11 and pivotal mounting 3, is provided with an oil groove or channel 13 communicating with the oil hole 14 in the hub 15 and also with the oil hole 16 in the hub 17. It 10 is obvious also that during the reciprocation of the rocker arm some of the oil carried in the groove will be swashed over the hub 15 and be carried on the web 12 to the oil hole 32 and thereby lubricate the ball and socket joint 5. A 15 bat-wing shaped scraper is indicated at 18, it having integral therewith the hooked finger 19 which forms the pivotal connection of the scraper with the body portion of the arm 2, the inner extremity of the finger resting within the 20 jaw-like bearing 20 formed upon the upper edge of the outer wall of the channel 13. As the rocker arm reciprocates up and down, the scraper on the down stroke scrapes on the periphery of the gear 6 and removes therefrom 25 a portion of the oil carried thereby and directs it into the channel 13 thereby providing lubrication for the pitman 11 and pivotal support 3 as well as the other moving parts of the rocker arm.

30 The power pinion is indicated at 21, it being screw-threadedly mounted upon the end of the shaft 22, extending within the housing 23 to the blades of the windmill not shown. This pinion shaft housing 23 is bolted to the oil reservoir by 35 means of the bolts 24, upon removal of which bolts, the entire pinion, shaft, and housing assembly may be removed through the end of the reservoir 1. An enlargement 25 is indicated on the upper surface of the pinion shaft housing, 40 which enlargement is hollow and communicates with an oil hole 26 at the outer end thereof. In that portion of the pinion shaft bearing which extends within the reservoir 1 there is another oil hole 27 so that adequate means is provided to 45 lubricate the shaft. Upon either side of the oil hole 27 within the housing 1 are provided a pair of upstanding webs 28 and 29, the latter being slightly higher than the other and fitting snugly within the ring 30 fixed to the back of the pinion 50 21. The thickness of the ring is but about half the depth of the pinion teeth, and thus between the teeth and under the ring are left openings 31, there being one of such between each pair of teeth, and which openings provide a passage for 55

oil into the channel between the webs 28 and 29 and to the oil holes 27 and 26 and thereby lubricate the pinion shaft 22. For the return of the oil to the reservoir, I have provided the return chamber 34 at the lower end of the inner wall of which is an opening 35 communicating with the return oil passage 33 formed in the under side of the pinion shaft housing and which passage communicates with the reservoir 1. Within the return chamber 34 there is a double oil slinger not shown to prevent leakage of oil through this end of the bearing. There may or may not be provided an opening in the bearing under the shaft so that oil may return through this opening to the reservoir.

Should the weather be cold and the oil not flow easily, the ring gear 6 would pick up the thick oil and transfer a portion of it to the pinion 21, and, if too thick to readily pass through the openings 31, the web 29, which extends within the ring 30, would scrape a sufficient quantity of the oil therefrom and direct it into the channel between the webs 28 and 29 to lubricate the pinion shaft.

25 The removal of the ring gear from the housing may be accomplished following the removal of the rocker arm assembly, by removing one of the cup bearings 8, when the ring gear may be slid laterally toward the side of the housing which 30 would free the end of the shaft 7 from the other side of the housing, when the gear could be tipped up and easily removed from the housing.

Having thus described my invention, what I claim and desire to secure by Letters Patent, is:

35 1. Lubricating means for the pinion shaft bearing of a windmill head comprising a housing about said shaft and partially extending within said head, a pinion and shaft within said housing, a ring on the rear face of the pinion, and 40 means for receiving oil from between the pinion teeth and under the ring and directing it to the shaft bearing.

2. A power pinion having a ring fixed to the rear face thereof, the radial distance between 45 the two peripheries of said ring being less than the height of the gear teeth, and the periphery of the ring being coincident with the periphery of the gear teeth.

3. A power pinion having a ring fixed to the 50 rear face thereof, the radial distance between the two peripheries of said ring being less than the height of the gear teeth and the inside diameter of the ring being greater than the distance between the roots of the teeth on opposite sides of 55 the gear, leaving openings between the teeth and under the ring.

4. Lubricating means for the pinion shaft bearing of a windmill head comprising a housing about said shaft and partially extending within said head, a pinion, and a shaft extending within said housing, a peripheral ring fixed to the rear 5 of said pinion, and a scraper web fixed to said housing and extending within said ring to remove oil therefrom as the ring revolves about the housing.

5. Lubricating means for the pinion shaft bearing of a windmill head, comprising a pinion and shaft therefor, a bearing housing about the shaft, oil openings through said housing communicating with said shaft, a ring on the rear face of the pinion, means for supplying oil to said pinion, 15 means on said housing extending within said ring for directing oil therefrom to said oil openings.

6. Lubricating means for the pinion shaft bearing of a windmill head, comprising a pinion and shaft therefor, a bearing housing about the shaft 20 having openings therein providing access of oil to said shaft, a ring on the rear face of the pinion, a scraper web on said housing contacting said ring for directing oil therefrom toward said openings, and an opening in the bottom of said 25 housing providing means for the return of oil from said shaft.

7. A pinion having a ring fixed to the rear face thereof, the diameter of the inside of said ring being greater than the distance between the 30 roots of the teeth on opposite sides of the gear, leaving openings between the teeth and under the ring.

8. The combination with a windmill head including cooperative bevel gears, one upon the driven shaft and one upon the drive shaft, of a separable housing for said head comprising a principal part surrounding both gears and the driven shaft, and a second part surrounding and forming a bearing for the drive shaft and extending partially within the principal part of the housing, said second part being externally attached to the principal part whereby removal of the drive shaft and second part of the housing may be accomplished simultaneously. 45

9. Lubricating means for a bearing comprising a shaft within said bearing, a pinion on said shaft, a peripheral ring fixed to the rear of the pinion, the diameter of the inside of the ring being greater than the distance between the roots of the 50 teeth on opposite sides of said pinion, leaving openings between the teeth and under the ring for the passage of oil, and means projecting from the bearing and within said ring for scraping oil therefrom as the ring revolves. 55

VAUGHAN L. ANDREW.
